UNITED STATES PATENT OFFICE.

CHAUNCEY MATLOCK, OF NEW YORK, N. Y., ASSIGNOR TO MONROE-LOUISIANA CARBON COMPANY, OF MONROE, LOUISIANA, A CORPORATION OF DELAWARE.

PROCESS AND APPARATUS FOR PRODUCING CARBON BLACK.

Application filed November 16, 1921. Serial No. 515,674.

The present invention relates to a process and apparatus for producing carbon black and more particularly to an improved furnace and burner construction for the production of carbon black by the partial combustion of natural gas hydrocarbons.

In the production of carbon black from natural gas it has been customary heretofore to dissociate and set free the carbon from the hydrocarbons by burning the gas in a number of small flames to which the entrance of air for supporting combustion is imperfect and in which the partial combustion may be checked by inserting in the flames a cool or chilled plate or surface. A portion of the carbon of the hydrocarbons is therefore set free and collects on the plate or may pass out of the flame without being oxidized and is thereafter separated from the gaseous products of combustion and collected in any suitable manner. The partial oxidation of the hydrocarbon gases may be carried on more efficiently and with a greater production of carbon in closed chambers or furnaces in which the supply of air and the other conditions of oxidation may be carefully regulated or adjusted. Difficulty is, however, sometimes experienced in the production of the better qualities of carbon black, because of the preheating of the gas in the burner tubes within the furnace by heat radiated or conducted downwardly from the combustion zone of the furnace which tends to crack or decompose the hydrocarbons and produce undesired carbon or coke in the burners.

One of the objects of the present invention is to provide a burner and supply pipes within a carbon black furnace by which the gas to be burned may be protected from preheating while within the burner.

Another object of the invention is to provide a method or process of burning hydrocarbons for the production of carbon black in which the gas is protected from preheating by the burning gases in the furnace.

Among other objects of the invention is to provide a burner particularly adapted for use in the production of carbon black and which may be readily removed from and inserted in a carbon black furnace while the furnace is in operation.

With these and other objects in view the invention comprises the process and appara-

tus described and set forth in the following specification and claims.

The various features of the invention are illustrated in the accompanying drawings in which:

Fig. 1 is a cross sectional elevation of a carbon black furnace embodying a form of the invention, the burners being shown on a somewhat enlarged or magnified scale with relation to the other part of the furnace to more clearly bring out their construction, and,

Fig. 2 is a vertical sectional view similar to that of Fig. 1 showing a modified form of burner.

In the present invention the hydrocarbon gas is introduced into the lower part of a combustion furnace and distributed by means of a number of burners. Air for supporting the partial combustion of the hydrocarbons is also introduced below, or at approximately the same height in the furnace as the burners, and mixes with the hydrocarbon gases and burns with them above the burners. The hydrocarbons are protected from preheating and partial or complete dissociation in the burners by covering the burners and the connecting burner pipes with a cooling jacket through which water or other cooling fluid may be circulated. Through this arrangement the entire reaction by which the carbon is liberated takes place above the burners and without being disturbed by uncontrolled reactions in the burners and burner pipes. The cooling jackets do not however, contact directly with the burning gases or flame in the upper part of the furnace and do not check this combustion as in the older, chill plate processes, the gases being removed from the upper part of the furnace without being chilled. In a modified type of the burner and connecting pipes the openings in the furnace through which the burner pipes pass, and the construction of the burner itself is so arranged that any individual burner may be removed while the furnace is in operation without stopping the operation of the furnace and cooling the furnace and burner.

Referring more particularly to the accompanying drawings the hydrocarbon gases from which carbon is to be liberated are supplied from a gas supply pipe 10 through a

controlling valve 12 to a burner pipe 14 extending into a furnace 15 and issue in separate streams through upright burners 16 and 18. Air for supporting the combustion of the hydrocarbons is supplied from an air supply pipe 20 through an opening 22 below the burners 16 and 18 and mixes with the gas jets or flames 24 above the burners. The main combustion of the gases takes place in the upper part 26 of the furnace without being influenced by any chilling action other than that caused by downward radiation. The hot products of combustion and the liberated carbon are removed through an outlet pipe 28 to any suitable separating device.

Some heat is however, radiated downwardly from the upper part of the furnace to the pipe 14 and the burners 16 and 18, the main portion of the heat being received by the pipe 14. To maintain the pipe 14 and the gases flowing therethrough below a cracking or dissociating temperature, the pipe is surrounded and enclosed by a cooling jacket 30 through which the burners 16 and 18 project. A cooling fluid such as water, steam, air, or other comparatively cool fluid is supplied to the jacket through a supply pipe 32 and is delivered to the extreme end of the jacket by means of an inner conduit or tube 34. From the outlet end of the tube 34 the cooling fluid passes between the walls of the jacket 30 and the outer surface of the pipe 14 to an outlet opening or draw-off pipe 36. Through this arrangement the hydrocarbon gases are delivered from the burners 16 and 18 without being decomposed or otherwise altered and in a condition in which they may be readily oxidized. Ordinarily it is not necessary to extend the water jacket to the outlets of the burners 16 and 18 although this may be done where desirable.

In the modification shown in Fig. 2 a type of burner is illustrated which may be readily and quickly inserted into and removed from the furnace without disturbing the furnace structure and therefore without the necessity of cooling the furnace. In this arrangement each burner has an individual supply pipe 38 extending through an opening 40 in the wall of the furnace 78 and turned upwardly through a quarter turn into the outlet or nozzle portion 42. The burner pipe 38 is surrounded by a cooling jacket 44 which is similarly curved upwardly for substantially a quarter turn. The cooling jacket is provided with an inlet pipe 46 and a distributing tube 48 similar to the tube 34 of the modification shown in Fig. 1. The burner pipe and jacket 44 are connected to the supply main 10 by means of a flanged union 50 which permits the burner to be readily disconnected from the supply pipe, the supply of gas being

shut off by a suitable valve not shown. When the burner and the jacket 44 are disconnected from the supply pipe 10 and the water supply pipe 46 the burner may be withdrawn through the opening 40 until the curved portion reaches the inner wall of the furnace. To withdraw the upright and curved portion of the burner and its jacket need only be swung upwardly permitting the curved portion of the jacket to pass through the opening without the necessity of providing an opening larger than the outside diameter of the jacket. The furnace is provided with a support 52 extending from the floor thereof to the curved portion of the burner and serving to hold the burner in its proper position without depending upon its fitting the opening 40 for this purpose.

The burner shown in Fig. 1 may also be disconnected from the supply pipes 10 and 32 by connecting it to these pipes through flanged unions 54 and 56 respectively but individual burners cannot be removed from the furnace while in operation, nor be removed as conveniently as in the modification shown in Fig. 2.

Through the above described invention the hydrocarbon gases are supplied to the combustion or reaction zone of the furnace in an unaltered and unchanged condition which permits their ready and complete mixture with the air supply. The troublesome stoppage of the burners through the deposition of coke and carbon deposits caused by the premature heating and decomposition of hydrocarbons in the burners is also avoided and a much smoother working of the process and apparatus is made possible.

Having described the invention what is claimed and desired to be secured by Letters Patent is:

1. An apparatus for producing carbon black which comprises a furnace arranged to admit an insufficient supply of air for complete combustion, openings in said furnace for the insertion of burners and burners having a horizontal portion, an upright portion and a curved connecting portion adapted to permit said burners to be inserted and removed through said openings.

2. An apparatus for producing carbon black which comprises a furnace, burner openings in said furnace, said openings having a bevelled edge and burners having a horizontal portion, an upright portion and a curved connecting portion arranged to permit said burners to be inserted and removed through said openings.

3. An apparatus for producing carbon black which comprises a furnace having openings in its lower part for the insertion of burners, an air supply opening positioned lower than said burners and burners having

an entering portion, an upright portion and a curved connecting portion arranged to permit the insertion and removal of said burners into said furnace.

- 5 4. An apparatus for producing carbon black which comprises a furnace having a number of burner openings, burners having an entering portion and an upwardly curved portion within said furnace to direct the gas 40
10 supply substantially upwardly and supports within said furnace adapted to support the portion of said burners within said furnace.

5. A process of producing carbon black which comprises supplying a stream of 15 gaseous hydrocarbons to a furnace, supplying air in quantities insufficient for complete combustion to said furnace, burning said hydrocarbons with said insufficient air supply while maintaining the base of said hydrocarbon 20 gaseous stream at non-carbonizing temperatures and removing the products of combustion from the furnace.

6. A process of producing carbon black which comprises supplying a stream of 25 gaseous hydrocarbon to a furnace; supplying air to said furnace in quantities insufficient for complete combustion; burning said hydrocarbon with said insufficient air supply shielding said hydrocarbons from 30 heating until exposed to said air supply; removing the products of combustion from the furnace; and finally separating the freed carbon from the removed gases.

7. That process of producing carbon black 35 which consists in supplying a stream of gaseous hydrocarbons to a furnace at tem-

peratures below that at which carbonization or decomposition takes place; supplying air in quantities insufficient for complete combustion to said furnace; burning said hydrocarbon with said insufficient air supply; shielding said hydrocarbons from heating by said combustion until brought into contact with said air; removing the products of combustion from the furnace; and separating the freed carbon from the removed gases. 45

8. That process of producing carbon black which consists in supplying a stream of 50 relatively cool hydrocarbon gases to a closed furnace; supplying air in quantities insufficient for complete combustion to said furnace; burning said hydrocarbon with said insufficient air supply surrounding said stream of hydrocarbons with a cooling 55 medium until exposed to mixture with said air; and separating the freed carbon from the burned gases.

9. The process of producing carbon black which consists in supplying a stream of 60 relatively cool gaseous hydrocarbons to a closed furnace; supplying air in quantities insufficient for complete combustion at a point below said hydrocarbon stream; burning the hydrocarbon with said insufficient 65 air supply shielding said stream of hydrocarbons from the heat of combustion in said furnace until released for mixture with said air supply; and separating the freed carbon from the burned gases. 70

In testimony whereof I affix my signature.
